UNITED STATES PATENT OFFICE.

EDWARD P. BERK, OF BUCYRUS, OHIO.

VULCANIZER.

1,123,223.

Specification of Letters Patent.

Patented Jan. 5, 1915.

Application filed October 24, 1913. Serial No. 797,076.

To all whom it may concern:

Be it known that I, EDWARD P. BERK, a citizen of the United States of America, residing at Bucyrus, in the county of Crawford and State of Ohio, have invented certain new and useful Improvements in Vulcanizers, of which the following is a specification.

This invention relates to certain new and useful improvements in vulcanizers and relates more particularly to improved means for transmitting and retaining the heat during the vulcanizing process and to also concentrate the heat and cause same to be consequently intensified at the vulcanizing points.

Further the invention aims to provide a vulcanizer that has means incorporated therein for enabling the fuel to be easily, quickly and conveniently poured thereinto, and to also provide a gage that instantly enables the quantity of fuel in the vulcanizer to be determined.

In the drawing: Figure 1 is a fragmentary perspective view of a vehicle wheel, showing the present invention operatively applied thereto; Fig. 2 is a top plan view, parts being broken away and shown in section, of the device when used to vulcanize inner tubes; Fig. 3 is a plan view of one of the heat transmitting elements; and Fig. 4 is a side elevation, partly broken away and in section showing the vulcanizer supported from a post or the like.

The present invention is an improvement on the subject matter of an application filed by me November 8, 1912, Serial No. 730,147.

The vulcanizer consists of a body 1 that has apertured ears 2 which receive L-shaped bolts 3, and eye bolts 4, which bolts are engaged with chains 5 which serve to secure the body to a vehicle wheel, the chains being tightened by means of thumb or wing nuts.

6. The body 1 has side flanges 7, a top flange 8 and a bottom flange 9, the latter at 45 its forward end being extended upwardly and outwardly at 10 to form an inclined lip, which latter with the flanges 9, and 7 provides a fuel chamber 11. A plate 12 is secured to the side flanges 7 and has its lower 50 portion inclined inwardly and downwardly at 13 so as to form a mouth 14 which allows the fuel, preferably gasolene, to be easily, quickly and conveniently poured into the chamber 11, as is obvious from inspection of 55 Figs. 1 and 4.

Arranged between the plate 12 and the

wall 15 of the body 1 are a series of vertical spaced heat transmitters 16 that are of zig-zag outline and which have their sides tapering toward the wall 15. By utilizing 60 heat transmitters of zig-zag form, a greater area is presented to the heat with the result that a larger proportion of the heat is thereby retained by same and by having the sides of the transmitters of tapering 65 form the heat is quickly conducted from the outer edges of the transmitters to the inner edges of same thereby concentrating the heat at said inner or thin edges of the transmitters with the result that the heat 70 is intensified where said inner edges contact with the wall 15, which latter provides the vulcanizing face for the device. The zig-zag transmitters due to their spaced relation provide tortuous heat flues, causing 75 the heat to ascend in paths that most effectively act on and raise the temperature of the transmitters.

A gage 17 is secured to the wall 15 between the bottom flange 9 and the free 80 edge of the lip 10 to indicate the level and hence the quantity of liquid fuel in the chamber 11, the gage consisting of a graduated element or scale which is visible through the mouth 14.

In Fig. 2 of the drawings, the vulcanizer is shown in use with an inner tube, in which use, a plate 18 is used to take the place of the outer casing of the tire shown in Fig. 1, the bolts 3 engaging pins 19 in slots 20 90 formed in ears 21 borne by plate 18 while the eye-bolts 4 engage through apertured ears 22 also borne by plate 18 to clamp the inner tube against the vulcanizing wall or face 15. The chain in this use of the invention is thrown over the top of a post as depicted in Fig. 4 to support the device in 95 upright operative position.

What is claimed is:

1. In a vulcanizer, a body having a vulcanizing face, a plate spaced from said face, and a multiplicity of heat transmitters disposed lengthwise of the plate and body and having their front and rear edges engaged with said plate and face, each of said heat 100 transmitters being of continuous zig-zag formation to form a multiplicity of tortuous heat flues therebetween, and having their sides tapered inwardly toward the vulcanizing face to provide extremely thin 105 edges at their points of contact with said face.

2. In a vulcanizer, a body having a vulcanizing face, a plate spaced from said face, a fuel chamber at the base of the plate having a lip that extends adjacent to the lower end of the plate, said plate having its lower end inclined downwardly and rearwardly toward the vulcanizing face and being spaced from the upper edge of the lip to form a mouth which enables liquid fuel to be poured into the chamber.
3. In a vulcanizer, a body having a vulcanizing face, a plate spaced from said face, a fuel chamber at the base of the plate having a lip that extends adjacent to the lower end of the plate, said plate having its lower end inclined downwardly and rearwardly toward the vulcanizing face and being spaced from the upper edge of the lip to

form a mouth which enables liquid fuel to be poured into the chamber, and a gage 20 carried by the vulcanizing face and being visible through said mouth.

4. In a vulcanizer, a body having a vulcanizing face, a plate inclined relative to and spaced from said face, and irregularly 25 formed heat transmitting means between the plate and said face, said means being thick adjacent the plate and thin where it engages the vulcanizing face.

In testimony whereof I affix my signature in presence of two witnesses.

EDWARD P. BERK.
